Attorney

UNITED STATES PATENT OFFICE.

JAMES M. NORMAN, OF ATLANTA, GEORGIA, ASSIGNOR TO DOWMAN-DOZIER MFG. CO.,
OF ATLANTA, GEORGIA, A CORPORATION OF GEORGIA.

METAL PROTECTION FOR BUILDING WALLS.

Application filed November 4, 1922. Serial No. 599,017.

To all whom it may concern:

Be it known that I, JAMES M. NORMAN, a citizen of the United States, and resident of Atlanta, in the county of Fulton and 5 State of Georgia, have invented certain new and useful Improvements in Metal Protection for Building Walls, of which the following is a specification, reference being had therein to the accompanying drawing.

10 In the construction of fireproof or approximately fireproof buildings it is common to provide metal parts to be applied at windows and door openings to hold the plaster securely upon the walls and to protect the edges and close any crevice between 15 the frame and the adjacent portion of the wall.

The general object of this invention is to provide at low cost simple, easily applied 20 and effective devices for the purposes suggested.

In the accompanying diagrammatic drawings,

Figure 1 is a horizontal cross section of 25 one side of a door frame and the adjacent portion of the wall;

Fig. 2 is a perspective view of a plaster-protecting strip or plate detached from the wall;

30 Fig. 3 is a section similar to Fig. 1 but showing in certain parts modified constructions.

In these figures, A represents partition studs, B, C, and D a jamb, stop, and door 35 member, all indicated in position by dotted lines, and usually of hollow metal or wood metal sheathed. Upon each of the opposite faces of the studs A is secured, e. g. by nails

A', a broad sheet metal strip E having its 40 marginal portion adjacent to the jamb bent abruptly outward and then backwardly to form a web F at the edge of a plaster coat G and a web H parallel to the body of the strip and externally flush with the outer 45 face of that coat. In the body of the strip many segments are cut free on three sides to form spaced tongues I, I' which are all pressed outward in curved form, as shown. These tongues preferably extend

50 outward to a distance a little more than half the plaster's thickness and their free marginal portions are curved slightly back toward the body of the strip, from which they are widely separated, to form a series

of broad hooks so far separated from the strip and from each other that plaster of proper consistency being applied in the usual way will fully envelop the hooks, the latter thus becoming embedded in the body of the plaster, that portion under the hook 55 being integral and continuous on each side with the body of the coat. Preferably, the hooks are turned in different directions, those of the first pair, for example, being oppositely turned outwardly, and those of 60 the next pair I' being inwardly turned, and so on.

The plaster coat cannot, then, move from the wall without the tearing out bodily from the inner face, by the many hooks of numerous integral portions of the plaster coat. It follows that the plaster, no matter how jarred in use, is never detached. At the same time the margin of the plaster coat is 70 fully protected by the webs F, H. In some cases the plaster does not extend to or over the jamb, and in that case I use one of the very old and common forms of hollow metal corner moldings J, K, L, each having preferably one broad, plane, inwardly turned 75 marginal portion to rest against the adjacent jamb or plaster face to aid in accurately holding the molding while it is being secured by screws M or the like.

If desired, the protecting margin of the strip covering the edge of the plaster coat may itself extend over the jamb as shown at N, Fig. 3, and being bent back, if desired in the form of one of the moldings above mentioned, the quarter round form being 80 shown.

What I claim is:

1. For use in connection with door and window frames in the walls of buildings, a sheet metal plate having a plane body 95 adapted for attaching flatwise to such frame and provided along the side adjacent to said opening with a hook-like flange forming with the body a groove adapted to be filled by mortar constituting a plaster wall-coat, 100 and further having along the middle region of said body a series of spaced, integral, laterally and terminally open hooks projecting to the middle region of the space bounded by the main surfaces of the plaster coat. 105

2. For protecting and holding plaster around a window or door frame, a sheet metal strip adapted to be secured flatwise

- to one face of the frame and having a plane body with an integral marginal flange bent back upon itself into a plane parallel to and at a plaster coat's thickness from said body, 5 said body having in its middle region sets of oppositely turned laterally and terminally open integral slightly resilient hooks projecting into the middle portion of the space between said body and said plane.
- 10 3. A plaster securing and protecting sheet metal strip secured, flatwise, to a frame fixed in a building wall opening and provided with a series of central, integral portions cut free on three sides and pressed outward, 15 forming pairs of oppositely turned, laterally open hooks under which mortar may pass unobstructed at all parts of the free margins, whereby open hooks are embedded

in an otherwise continuous and homogeneous plaster wall. 20

4. A plaster holding and protecting sheet metal strip secured, flatwise, to a frame fixed in an opening in a building wall and provided with a series of central integral portions each cut free on three sides and bent 25 outward forming laterally and terminally open hooks under which plastic mortar will pass, unobstructed, at all parts of the free margins and form a continuous mass centrally enclosing the hooks, and further provided with an integral marginal flange bent back upon itself to cover the edge of the 30 plaster coat.

In testimony whereof I hereunto affix my signature.

JAMES M. NORMAN.
